Primary Examiner — Mojtaba Tehrani(74) *Attorney, Agent, or Firm* — Hunton Andrews Kurth LLP(57) **CLAIM**

The ornamental design for a gas-pedal portion of a pistol as shown and described.

DESCRIPTION

FIG. 1 is a left front top perspective view of a gas-pedal portion of a pistol showing our new design;

FIG. 2 is a right rear bottom perspective view thereof;

FIG. 3 is a front view thereof;

FIG. 4 is a rear view thereof;

FIG. 5 is a right side thereof;

FIG. 6 is a left side view thereof;

FIG. 7 is a top view thereof; and,

FIG. 8 is a bottom view thereof.

The broken lines are for the purpose of illustrating environment and form no part of the claimed design.

1 Claim, 6 Drawing Sheets(56)
